UNITED STATES PATENT OFFICE

CHARLES S. BAKER, OF CORNING, NEW YORK, ASSIGNOR TO INGERSOLL-RAND COMPANY, OF JERSEY CITY, NEW JERSEY, A CORPORATION OF NEW JERSEY

COMPRESSOR-VALVE LIFTER

Application filed September 14, 1929. Serial No. 392,718.

This invention relates to compressors, but more particularly to a compressor valve lifter for opening an inlet valve of a compressor when the pressure within a storage receiver into which the compressor discharges attains a certain predetermined pressure.

The objects of this invention are to improve upon valve lifters of this type, to increase the certainty of operation, to render the mechanism positive in action, to eliminate the chances of leakage of the actuating pressure fluid from the valve lifter, and to secure an efficient and rugged structure fully capable of rendering service for prolonged periods of time without requiring frequent inspections or repairs thereto.

Other objects will be in part obvious and in part pointed out hereinafter.

The figure in the accompanying drawing is a sectional elevation of a valve lifter constructed in accordance with the practice of the invention and showing the valve lifter in its assembled position in a compressor.

Referring more particularly to the drawing, A represents a portion of a compressor having outer and inner walls B and C spaced with respect to each other to form therebetween a passage or chamber D through which atmospheric air may enter the compressor.

In the walls B and C are coaxial openings E and F respectively. The opening F is intended to accommodate a plate valve assembly, designated generally by G and comprising a valve seat H and a stop plate J spaced therefrom. Between the stop plate J and the valve seat H is a valve plate K for controlling ports L in the valve seat H. The stop plate J may be provided with the usual sockets O for the reception of springs P which act against the valve plate K for returning the valve plate K to its seat and for holding it thereon during the compression stroke.

The stop plate and the valve plate may be clamped together in any suitable manner, as for instance, by a bolt Q extending through the stop plate and the valve seat and having a nut R threaded thereon to clamp these elements together.

In order to hold the valve assembly G securely in position in the opening F, a valve

cage S is disposed in the opening E to seat against the valve seat H and has a flange T provided with suitable apertures U to accommodate bolts V which may be threaded into the wall B to draw the valve cage S firmly against the valve seat H. The skirt W of the valve cage may be of the well known type having the usual ports X therein to provide passages for the atmospheric air to the valve.

Disposed within the skirt W is a spider Y having the usual fingers Z which extend through the ports L and are adapted to bear against the valve plate K for unseating the said plate. The fingers Z may be of such length that when the spider is in its retracted position, said fingers will be out of contact from the valve plate K. The means whereby the fingers are held in this position consists of a spring b acting with one end against the spider Y and with its other end against the valve seat H.

In accordance with the present invention means are provided for actuating the fingers Z against the valve plate K for unseating said valve plate and thus unloading the compressor whenever the pressure in a storage receiver (not shown) to which the compressor may be connected reaches a certain predetermined value. To this end the valve cage S is provided with a cavity c forming a pressure chamber which may communicate with a source of pressure fluid supply, as for instance, the hereinbefore mentioned storage receiver, through a passage d in the valve cage S and a connection e threaded in the outer end of the passage d.

Preferably the passage d opens into the pressure chamber c at a point adjacent the entrance of the pressure chamber so that any moisture entrained by the pressure fluid and which may be precipitated to the lowermost point of the pressure chamber will again be blown from the pressure chamber by the exhaust pressure fluid. The point of communication between the passage d and the pressure chamber c may, however, be varied with the position of the valve cage, so that, irrespective of the position in which the said valve cage may be placed, the passage d will open

into the lowermost point of the pressure chamber *c*.

At the open end of the pressure chamber *c* is a guide *f* comprising a flange *g* and an extension *h* having a bore *j* therein. In the assembled position the flange *g* overlies the end of the pressure chamber *c* and the extension *h* projects into the said pressure chamber. The guide *f* may be secured to the valve cage *S* in any suitable manner, as for instance, by bolts *k* which extend through the flange and are threaded into the valve cage.

The bore *j* in the guide *f* serves as a guide for a rod *o* which may be threaded into the spider *Y* or otherwise suitably secured thereto and extends with its other or free end to a point above the extension *h*. On this end of the rod *o* is disposed a head *p* having a bore *q* therein to receive slidably the end of the rod *o*. The outermost end *r* of the head *p* constitutes a pressure surface against which pressure fluid in the pressure chamber *c* may act for pressing the fingers *Z* against the valve plate *K*.

In order to effectively avoid communication between the pressure chamber *c* and the bore *j* a collapsible diaphragm or sylphon *s* is interposed between the head *p* and the flange *g* of the guide *f*. The one end of the sylphon *s* may be suitably connected to the head *p* and to the other end of the sylphon *s* may be secured a plate *t*. Preferably the outer portion of the plate *t* is disposed between the flange *g* and the valve cage *S*, and between this outermost portion of the plate and the valve cage may be interposed a gasket *u* to form a fluid tight joint between the plate *t* and the valve cage.

In order to assure a pressure within the sylphon *s* of the same value as that existing in the passage *D*, the flange *g* is provided with a port *v* and the plate *t* is provided with a bore *w* through which the extension *h* extends, and said bore *w* is of such proportions as to permit of free communication between the interior of the sylphon *s* and the passage *D*.

During the normal operation of the compressor to which the invention may be applied and during the time the pressure fluid in the storage receiver is below the maximum predetermined value which it is desired to maintain therein, the fingers *Z* will be held in the retracted position against the flange *g* by the spring *b* and thus free from the valve plate *K*. The valve plate *K* will then be free to reciprocate in accordance with the movement of the compressor piston to admit atmospheric air into the compressing element and to form a closure for the ports *L* during the compression stroke of such element.

The parts comprising the valve lifter and the elements directly associated and adapted to move therewith will then remain stationary until the pressure in the storage receiver reaches its maximum value. When

this condition occurs pressure fluid may be admitted through the connection *e* and the passage *d* into the pressure chamber *c* by suitable controlling mechanism (not shown) to act against the pressure surface *r* of the head *p*.

Upon the exposure of the pressure surface *r* to the pressure fluid the force exerted by the spring *b* will be overcome and the fingers *Z* will be pressed against the valve plate *K* to hold said valve plate open and permit uninterrupted communication between the passage *D* and the compressor cylinder.

As long as the pressure in the pressure chamber *c* exceeds that which the spring *b* may exert, the valve plate *K* will be held in the open position. However, upon the reduction of the pressure in the storage receiver the spring *b* will act to again move the fingers *Z* out of contact from the valve plate *K*, and the said valve plate may then again perform its intended function. The pressure fluid utilized for depressing the fingers *Z* may then be exhausted from the pressure chamber in a well known manner and during its exit from the pressure chamber will remove any such moisture as may have previously been conveyed thereby into the pressure chamber.

The present invention has been found to be an unusually efficient device for its intended purpose and possesses the desirable features of simplicity of construction and freedom from developments of defects usually occurring in devices of this type after some usage.

I claim:—

1. Means for actuating a valve lifter for compressors of the type having fingers adapted to bear against the valve, comprising a valve cage having a pressure chamber, a guide secured to the cage and having a bore, a rod secured to the fingers and extending slidably through the bore, a plate clamped between the guide and the valve cage, a head on the rod and adapted to be exposed to pressure fluid for pressing the fingers against the valve to unseat said valve, means interposed between the head and the plate forming an enclosure for the bore to prevent communication between the pressure chamber and the bore, and vent means in the plate and guide to permit constant communication between the enclosure and that portion of the valve cage lying exterior of the pressure chamber.

2. Means for actuating a valve lifter for compressors of the type having fingers adapted to bear against the valve, comprising a valve cage having a pressure chamber, a guide having a flange secured on the valve cage, a bore in the guide, a rod secured to the fingers and extending slidably through the bore, a head on the rod and subjected to pressure fluid in the chamber for pressing the fingers against the valve to unseat said valve, a collapsible diaphragm secured at one end to the head forming an enclosure for the bore,

a flange on the other end of the diaphragm clamped between the flange on the guide and the valve cage to prevent communication between the pressure chamber and the bore, and 5 vent means in said flanges to provide free communication between the enclosure and the atmosphere.

3. Means for actuating a valve lifter for compressors of the type having fingers 10 adapted to bear against the valve, comprising a valve cage having a pressure chamber, a guide having a flange secured to the valve cage and overlying the end of the pressure chamber, a bore in the guide, a rod connected to the fingers and extending slidably 15 through the bore, a head on the rod seated loosely on the rod, a plate clamped between the valve cage and the flange, a collapsible diaphragm connected to the head and to the 20 plate forming an enclosure for the bore to prevent communication between the pressure chamber and the bore, vent means in the plate and guide to permit constant communication between the enclosure and that portion 25 of the valve cage lying exterior of the pressure chamber, and a passage in the valve cage for admitting pressure fluid into the pressure chamber at a point against the plate.

30 In testimony whereof I have signed this specification.

CHARLES S. BAKER.
